KARL F. NYSTROM, OF MONTREAL, QUEBEC, CANADA, ASSIGNOR TO WILLIAM H. MINER,
OF CHAZY, NEW YORK.

FRICITION DRAFT-RIGGING.

1,303,372.

Specification of Letters Patent. Patented May 13, 1919.

Application filed July 1, 1918. Serial No. 242,807.

To all whom it may concern:

Be it known that I, KARL F. NYSTROM, a subject of the King of Sweden, residing at Montreal, in the Province of Quebec and Dominion of Canada, have invented a certain new and useful Improvement in Friction Draft-Rigging, of which the following is a full, clear, concise, and exact description, reference being had to the accompanying drawings, forming a part of this specification.

This invention relates to improvements in friction draft rigging.

One object of the invention is to provide a relatively cheap friction gear for railway draft riggings wherein the usual casing or housing for the spring formed integrally with the shell, is eliminated.

Another and more specific object of the invention is to provide a friction gear for railway draft riggings wherein one of the shock absorbing springs is utilized as a column member to resist movement of the friction shell after a predetermined limited amount.

In the drawing forming a part of this specification, Figure 1 is a horizontal, sectional view of a portion of a railway draft rigging showing my improvements in connection therewith. Figs. 2 and 3 are vertical, transverse, sectional views taken on the lines 2—2 and 3—3, respectively of Fig. 1.

In said drawing, 10—10 denote channel or center draft sills of a railway car, to the inner faces of which are secured the well known form of rear stop lugs 11—11. Also secured to the inner faces of said sills are front stop castings 12—12 having main front shoulders 13—13, auxiliary front shoulders 14—14 for the friction shell, and limiting stop shoulders 15—15. The draw bar 16 is operatively connected to the shock absorbing mechanism proper by a vertical yoke 17 of well known form and said yoke together with the other parts of the mechanism enclosed therewithin is supported by a detachable saddle plate 18.

The shock absorbing mechanism proper, as shown, includes a relatively short friction shell 19, a plurality of friction shoes 20, wedge 21, front follower 22, rear follower 23, outer spring 24, intermediate spring 25 and inner spring 26. In addition, there are the well known anti-friction rollers 27 inter-

posed between the wedge 21 and shoes 20, a retaining bolt 28 and a small washer 29.

As clearly evident from an inspection of Fig. 1, the friction shell 19, at its inner end, is provided with laterally extended relatively heavy shoulders 30 which normally engage the auxiliary front stops 14—14. The shoulders 30 are normally spaced from the limiting stops 15 a distance corresponding to the permissible compressive movement of the spring 24, so that, the shell 19 will be limited in its inward movement simultaneously by the limiting stops 15 and the spring 24 just as the latter goes solid but before it can be compressed injuriously or beyond its elastic limit. As apparent from the foregoing, the spring 24 bears at its forward end against the shell 19 so as to yieldingly resist movement of the latter for a predetermined distance, the rear end of said spring 24 bearing against the follower 23. The other two springs 25 and 26 bear against the friction shoes at their forward ends, the spring 25 directly and the inner spring 26 indirectly through the washer 29.

The operation is as follows: Upon buffing movement, it is evident that all of the friction elements including the friction shell, will move rearwardly as a unit without frictional action and all of the three springs 24, 25 and 26 simultaneously compressed until the shell 19 engages with the limiting stops 15 and the spring 24 becomes solid and acts as a column member against further movement of the shell. Thereafter, continued inward movement of the draw bar and follower 22 will actuate the friction elements 20 and 21 with respect to the friction shell 19. In this manner, I obtain a relatively high spring capacity only during the preliminary limited movement of the shell 19 during which all three springs are utilized and thereafter obtain a higher resistance because of the action of the friction elements. In draft, it is evident that the friction shell 19 will be held stationary and no true frictional capacity is obtained. However, in the draft action, all three springs are again compressed simultaneously so as to obtain the high spring capacity, which action continues until the spring 24 becomes solid. With the arrangement and action described, it is evident that I obtain the necessary high capacity under buff with the lighter capacity

under draft. Furthermore, the construction enables me to do away with the usual spring casing or cage formed integrally with the friction shell and therefore the shell may be 5 made much cheaper than the combined casting heretofore employed. This effects a material saving both in initial cost and in the case of repairs. Furthermore, the spring 10 which is substituted for the casting provides additional spring capacity and becomes a shock absorbing element in replacing the usual spring casing that serves merely the function of a column.

Although I have herein shown and described what I now consider the preferred manner of carrying out the invention, the same is merely illustrative and I contemplate all changes and modifications that come within the scope of the claims appended 20 hereto.

I claim:

1. In a draft rigging for railway cars, the combination with draft sills and front and rear stop means, of a friction shell movable 25 in buff and stationary in draft, spring means for yieldingly resisting the movement of said shell in buff, friction elements coöperable with said shell, and spring means for yieldingly resisting relative movement between the shell and friction elements during 30 the latter part of the buffing movement only.

2. In a draft rigging for railway cars, the combination with draft sills and stop means, of a friction shell movable relatively to the 35 sills in one direction only from normal, friction elements coöperable with said shell, a plurality of nested springs, all of said springs being compressed simultaneously and to the same amount in draft, all of said 40 springs being compressed simultaneously

during a part only of the buffing action and a part only of said springs for the entire buffing action.

3. In a draft rigging, the combination with draft sills and front and rear stop means, of a front follower, a rear follower, a relatively short friction shell located between said followers, means for holding said shell stationary under draft, said shell being movable rearwardly under buff for a limited distance, friction elements coöperable with said shell, a spring interposed between said shell and the rear follower and yieldingly resisting movement of the shell for said limited amount, and additional 55 spring means interposed between said friction elements and the rear follower.

4. In a draft rigging, the combination with draft sills having front main stops, front auxiliary stops and rear main stops, of a front follower coöperable with the front main stops, a rear follower coöperable with the rear main stops, a friction shell having shoulders coöperable with said auxiliary front stops, said shell having a limited inward movement under buff, a spring interposed between said shell and the rear follower and adapted to be compressed for a limited distance under both buff and draft, friction elements coöperable with the shell, 65 and another spring interposed between said elements and the rear follower and adapted to be compressed simultaneously with the first named spring and for the same amount under draft.

In witness that I claim the foregoing I have hereunto subscribed my name this 19th day of June, 1918.

KARL F. NYSTROM.
